UNITED STATES PATENT OFFICE

124,163

DESIGN FOR A COMBINED SHAWL AND HOOD

Julius Berger, Irvington, N. J.

Application March 8, 1940, Serial No. 90,763

Term of patent 7 years

To all whom it may concern:

Be it known that I, Julius Berger, a citizen of the United States and a resident of the city of Irvington, county of Essex, and State of New Jersey, have invented a new, original, and ornamental Design for Combined Shawl and Hood, of which the following is a specification, reference being had to the accompanying drawing, forming part thereof.

Fig. 1 is a plan view of a combined shawl and hood showing my new design; and

Fig. 2 is a perspective view of the same showing the shape which the hood portion thereof assumes when in use.

I claim:

The ornamental design for a combined shawl and hood, as shown.

JULIUS BERGER.
